(57) **CLAIM**

The ornamental design for goggles adapted to receive a device, as shown and described.

DESCRIPTION

FIG. 1 is an exemplary diagram showing the use of the goggles adapted to receive a device in an environment, the broken lines being shown for illustrative purposes only and form no part of the claimed design;

FIG. 2 is a front perspective view of the goggles adapted to receive a device, showing my new design;

FIG. 3 is a front view thereof;

FIG. 4 is a rear view thereof;

FIG. 5 is a side view thereof, with the opposite side view being a mirror-image thereof;

FIG. 6 is a top plan view thereof; and,

FIG. 7 is bottom plan view thereof.

In all figures, any showing of the environment and/or drawing disclosure and/or device by broken lines is for illustrative purposes only and forms no part of the claimed design.

1 Claim, 7 Drawing Sheets
